No. 752,462.

PATENTED FEB. 16, 1904.

E. I. MOREY,
TAPPET FOR STAMP MILLS.
APPLICATION FILED JULY 29, 1903.

NO MODEL.

UNITED STATES PATENT OFFICE.

EDWARD IVES MOREY, OF TELLURIDE, COLORADO.

TAPPET FOR STAMP-MILLS.

SPECIFICATION forming part of Letters Patent No. 752,462, dated February 16, 1904.

Application filed July 29, 1903. Serial No. 167,408. (No model.)

To all whom it may concern:

Be it known that I, EDWARD IVES MOREY, a citizen of the United States, and a resident of Telluride, in the county of San Miguel and State of Colorado, have invented a new and Improved Tappet for Stamp-Mills, of which the following is a full, clear, and exact description.

This invention relates to improvements in tappets for stamp-mill stems, an object being to provide a tappet so constructed as to be readily adjusted lengthwise of the stem and also to be adjusted to the possible reduction of circumference due to the wear of the stem in moving in its guides, and, further, to so construct a tappet that it will be practically impossible to displace it when locked in place.

I will describe a tappet for stamp-mills embodying my invention and then point out the novel features in the appended claims.

Reference is to be had to the accompanying drawings, forming a part of this specification, in which similar characters of reference indicate corresponding parts in all the figures.

Figure 1 shows a portion of a stamp-mill with a tappet embodying my invention on the stem thereof. Fig. 2 is a side elevation of the tappet on an enlarged scale. Fig. 3 is a section on the line 3 3 of Fig. 4. Fig. 4 is a section on the line 4 4 of Fig. 3, and Figs. 5 and 6 are perspective views of locking-gibs employed.

Referring to the drawings, 5 designates a sleeve or cylinder the interior diameter of which is slightly greater than the stem 6 on which it is to be placed, the object of which will hereinafter appear. On its outer side the sleeve has longitudinally-extended ribs 7 8 9, and the ends of these ribs connect with end flanges 10. On the inner side and in alignment with the ribs 7 8 9 the sleeve is provided with longitudinal recesses 11 12 13, the outer walls of the recesses 11 and 12 being tapered with relation to the axis of the sleeve, and these tapers extend in opposite directions.

Movable in each recess or chamber 11 12 is a longitudinally-tapered gib 14, the inner surface of which is conformed transversely to the stem. The ribs 7 8 are provided with transverse openings 15, into which head por-

tions 16 of the locking-gibs extend, these openings 15 being at opposite ends of the sleeve. Each rib 7 8 at one end of its opening 15 is provided with an outward opening 17, through which a suitable tool may be inserted for releasing the gib. For convenience in inserting an operating-tool a wall of said opening 17 is inclined, as indicated at 18.

Arranged between the locking-gibs 11 12 and seated in the recess 13 is a straight supplemental gib 19, which serves in coacting with said gibs 11 and 12 to center the tappet on the stem, and the stem-engaging surface of this gib 19 may be kerfed or roughened, as indicated in Fig. 6. It may be at times necessary—that is, when the stem becomes worn circumferentially—to adjust the gib 19 inward, and therefore I provide the rib 9 at about its center with an outward opening 20, through which a shim 21, of cardboard or other suitable material, may be passed.

It will be noted that the opposite end walls of the opening 20 are arranged on an incline, so that the shim may be placed in position by putting one of its ends through said opening 20 and sliding the same upward between the gib and wall of the recess, and then the other end may be similarly inserted.

In securing the tappet to the stem the tapered gibs are to be forced lengthwise, which may be done by passing a wedge-shaped tool through the opening 15 to engage with the end of the head 16. Such a wedge-shaped tool is indicated at α in Fig. 2.

When it is desired to loosen the sleeve for the purpose of adjustment, a suitable tool is to be inserted through the opening 17 to engage with the head 16, then with a slight tap of a hammer or the like the gib will be loosened.

As before stated, the opening through the sleeve is of somewhat larger diameter than the diameter of the stem. Therefore there are no parts bearing on said stem excepting the gibs, and thus the sleeve is not liable to wear.

It is obvious that a tappet embodying my invention may be very quickly adjusted both lengthwise of the stem and around the same.

Having thus described my invention, I claim as new and desire to secure by Letters Patent—

1. A tappet comprising a sleeve adapted to

receive a stem or shaft, and tapered locking-gibs movable in and longitudinally of the sleeve, the tapers being in opposite directions, and the said gibs being spaced apart circumferentially of the sleeve.

2. A tappet comprising a sleeve adapted to receive a stem or shaft, a plurality of channels formed in the inner side of said sleeve, said channels being spaced apart circumferentially of the sleeve, tapered gibs in certain of said channels, the tapers being extended in opposite directions, and a straight gib in another of said channels.

3. A tappet for a stamp-mill stem, comprising a sleeve, longitudinal ribs on the outer surfaces of said sleeve and spaced apart, the said sleeve at its inner side having recesses in alignment with said ribs, transverse openings in certain of said ribs, wedge-shaped gibs movable in the recesses in alignment with the ribs having said transverse openings, the said gibs having head portions extended into the transverse openings, and a straight gib in another of said recesses.

25 4. A tappet for a stamp-mill stem, comprising a sleeve, longitudinal ribs on the outer sur-

face of said sleeve, the inner side of the sleeve being provided with recesses in alignment with the ribs, each of said ribs having an outward or lateral opening from its recess, tapered gibs 30 movable in certain of said recesses and having outwardly-extended head portions, the tapers being extended in opposite directions, the ribs in which said tapered gibs operate also having transverse openings into which said head portions extend, a straight gib in another of said recesses, and a shim arranged in said other recess.

5. A tappet for a stamp-mill stem, comprising a sleeve having an interior diameter 40 slightly larger than the diameter of the stem, the said sleeve having spaced longitudinally-disposed recesses in its inner side, and locking-gibs arranged in said recesses and engaging with the stem.

In testimony whereof I have signed my name to this specification in the presence of two subscribing witnesses.

EDWARD IVES MOREY.
